UNITED STATES PATENT OFFICE.

FREDERICK HACHMANN, OF CHICAGO, ILLINOIS, ASSIGNOR TO FRANK R. SINNING,
OF RAMSEY, ILLINOIS.

TRACK LINER.

Application filed September 28, 1922. Serial No. 591,024.

To all whom it may concern:

Be it known that I, FREDERICK HACHMANN, a citizen of the United States; and a resident of the city of Chicago, in the 5 county of Cook and State of Illinois, have invented certain new and useful Improvements in a Track Liner; and I do hereby declare that the following is a full, clear, and exact description of the same, reference 10 being had to the accompanying drawings, and to the numerals of reference marked thereon, which form a part of this specification.

This invention relates to an improved 15 track liner of a type which is particularly adapted to be used in railway work to supplant the ordinary lining bar which is used in moving the track to its proper position.

It is an object of the present invention 20 to provide a track liner which may be used to exert a horizontal thrust either against the rails or the supporting means therefor.

It is also an object of this invention to 25 provide a device of the class described which is of relatively light weight and which may be conveniently carried from place to place.

It is a further object of this invention 30 to provide a track liner which may be easily set in position for effective operation and which is adapted to operate equally well with various size rails.

It is an important object of this invention 35 to provide a device of the class described which will act to exert an effective lateral thrust on the track and which may be conveniently and securely anchored.

Other and further important objects of 40 this invention will be apparent from the disclosures in the specification and the accompanying drawings.

The invention (in a preferred form) is 45 illustrated on the drawings and hereinafter more fully described.

On the drawings:

Figure 1 is a side elevation of a track liner embodying the principles of this invention.

50 Figure 2 is a side elevation, with parts in section, showing the track liner as applied directly to a rail.

Figure 3 is a side elevation, with parts 55 in section, showing the track liner engaging a tie.

Figure 4 is a top plan view of the track liner.

Figure 5 is a front elevation thereof.

Figure 6 is a slightly enlarged central vertical section through the track liner, with 60 parts in elevation.

Figure 7 is an enlarged detail section, with parts in elevation, on line 7-7 of Figure 6.

As shown on the drawings: 65

A device embodying a preferred form of this invention is shown herein as comprising a base 1 having permanently mounted downwardly extending anchoring means 2 and 2^a thereon. The anchoring means 2 comprise spikes which are integral with the base 1, while the anchoring means 2^a comprises an arcuate sharpened flange which is mounted at the rear end of the base and which is especially adapted to prevent lateral rearward movement of the base. Extending from the front end of the base 1 and integral therewith are spaced arms 3 which have downwardly extending flanges thereon and the outer ends of which are joined by an integral rounded transverse portion 4, said arms together with said transverse portion providing a forward extension of the base 1 which is adapted to be engaged under a railway tie or rail, and the round portion 4 affording a handle whereby the device may be conveniently carried about from place to place. 75

Integral upwardly extending spaced portions 5 on the base 1 extend upwardly and toward the forward end of said base to a point above the arms 3 and afford a pivotal support for a lever 6 which is adapted to engage the rail or tie to move the track laterally when said lever is moved about its pivot point. This pivot point is formed in bosses 7 on the portions 5 by providing a bearing at 8 at the bottom of grooves 9 formed on the inner side of said bosses. Integral trunnions 10 formed on the lever 6 engage said bearing 8 so that said lever is pivotally supported in the bearing. Said trunnions 10 are flattened on their upper and lower sides so that, if desired, the lever may be rotated to substantially horizontal position and removed by sliding the trunnions 10 upwardly through the grooves 9. The lever 6 is cored out for lightness and is adapted to have an ordinary lining bar or similar lever 11 engage in its upper end 100 105 110

whereby sufficient leverage may be obtained to exert a large lateral thrust at the lower end of the lever when the same is rotated about its pivot point. Said lever 6 is provided with an indentation or cut-away portion at 12 to provide for clearance from the ball of a rail 13 when the same is engaged in the operative position indicated in Figure 2 and in order to reinforce the lever at the point weakened by said indentation 12 a rib 14 is preferably formed on the rear side thereof, as clearly shown in Figure 1. At the lower end of the lever 6 a second indentation or cut-away portion 15 is provided and the face of the lever at the lower side of said indentation is preferably provided with a series of grooves or notches 16 whereby there is no danger of the lever slipping when engaging the flange of the rail 13 in the manner shown in Figure 2. In order that the lever 6 may be engaged against the end of a tie 17, as for example when switch mechanism and the like prevent engagement of the rail 13, a projecting boss 18 is provided on the face of the lever between the indentations 12 and 15 in such a manner as to engage the end of the tie to move the same laterally when the lever 6 is rotated about its pivot point. The position for engagement with the end of a tie or the like is clearly shown in Figure 3. Means are provided for preventing the lever 6 from dropping out through the grooves 9 when it is being carried from place to place, said means comprising removable pins 19 which are best shown in Figure 4 and which are adapted to be engaged through the bosses 7 and the slots 9 above the bearing 8.

In order that the piece 1 may be very securely anchored against lateral movement, an additional anchoring means is provided, said anchoring means comprising a pair of pins 20 which are movably engaged through apertures in the base 1 between the portions 5 at the rear end of said base, the upper ends of said pins 20 being connected by an integral portion 21 which has its upper face rounded to permit convenient engagement thereof by any suitable tool which may be used for driving the pins 20 into the ground. In order to prevent said pins 20 from falling away from the piece 1 when the device is carried from place to place, a removable pin 22 is preferably provided which is engaged through apertures in said pins, as clearly shown in Figure 7.

In order that the entire device may be solidly positioned, a shoulder 23 is provided on an integral connecting portion 24 between the portions 5, said portion 24 extending from the piece 1 upwardly to a point where it forms the rear portion of the bearing 8. The shoulder 23, as will be evident from an examination of Figures 4 and 6, affords

means which may be engaged by the end of a bar or similar tool to facilitate the driving of the anchoring means 2 and 2^a into the ground. Outwardly extending flanges 25 which are integral with the base 1 and with the portions 5 serve to strengthen the device and afford means which may similarly be engaged by a bar or similar tool to drive the anchoring means into the ground. The front face of the lever 6 is provided with transverse spaced projecting lugs 30 which may be used to retain the ends of a bar which is placed between two oppositely faced levers 6 after said levers have been engaged under a rail and rotated to lift the same. It is of course obvious that the rail will thus be maintained in such lifted position.

The operation of the device will be obvious from the illustrations and from the foregoing description, it being only necessary to position the base 1, as shown in Figure 2, adjacent the track which is to be lined, engaging the flange of the rail 13 with the cut-out portion 15 of the lever 6 and outwardly rotating said lever about its pivot point. Similarly, in case it is not possible to position the device adjacent the rail itself, the end of the tie 17 may be engaged by the boss 18, as shown in Figure 3, and the rotation of the lever about its pivot point acts to shift the tie and track thereon laterally.

In using the device it is desirable to engage the arms 3 and the connecting portion 4 under the rail or tie as the case may be, and after the device is positioned, the same may be securely anchored by means of the anchoring means 2, 2^a and 20.

It will be noted that I have so constructed the pivot point in the device of this invention with reference to the base that a large effective component of lateral thrust is obtained without the necessity of blocking up the rear of the base by placing dirt and the like thereunder, as has been necessary in a former type of rail liner which is now in use. This effect is produced by forming the brackets so that there is substantially a wedge of material added thereto which results in a tilting forward of the pivot point.

It is also evident that the provision of the cut-out portion 12 makes it possible to operate my rail liner on various sizes of rails since there is no possibility of the ball of the rail engaging the lever.

The entire device may be constructed of cast metal with a minimum of machine work, and by providing strengthening ribs and flanges at weaker points, I have been able to produce a rail liner which is light and compact, and which may be economically manufactured.

In using this rail liner it is preferable to have three in operation at the same time,

and by the use of three of these devices it is possible to do the work of a large number of men that were formerly required in lining tracks, switches and the like with the 5 ordinary type lining bar.

I am aware that numerous details of construction may be varied through a wide range without departing from the principles of this invention, and I therefore do not 10 purpose limiting the patent granted otherwise than necessitated by the prior art.

I claim as my invention:

1. A track liner comprising a base, a lever pivotally fulcrumed upon said base, and having 15 a forwardly projecting toe and a projecting portion above said toe whereby a track engaging seat is formed therebetween

and a boss on said projecting portion for the purpose set forth.

2. A track liner comprising a base having a forwardly extending portion and anchoring tangs projecting downwardly from said base, a pair of arms rising from the rear of said base and curved forwardly so as to overhang the extension of said base, a jack lever having trunnions upon its rear side pivotally fulcrumed to said base, said lever having an indentation adapted for engaging the lower flange of a rail and a cut out portion for clearing the ball of said rail. 20 25 30

In testimony whereof I have hereunto subscribed my name.

FREDERICK HACHMANN.
